UNITED STATES PATENT OFFICE.

PETER MEYER, OF ST. PAUL, MINNESOTA.

LIQUID BRAKE.

Application filed October 30, 1922. Serial No. 597,809.

To all whom it may concern:

Be it known that I, PETER MEYER, a citizen of the United States, residing at St. Paul, in the county of Ramsey and State of Minnesota, have invented certain new and useful Improvements in Liquid Brakes, of which the following is a specification.

This invention relates to fluid brakes, and has for one of its objects to provide a novel construction in brake mechanism more particularly for use in connection with automobiles, which will be noiseless, durable, and will have no metal to metal frictional braking surfaces to become worn and require frequent renewal, and which will be self-lubricating and cheap of maintenance.

A further object of the invention is the provision of improved means in brakes of the class described, whereby a continuous brake action may be safely had by forcing a relatively small body of oil repeatedly through a variable orifice and communicating the back pressure thus created to the drive shaft, the construction of the device being such as to have all of the moving parts thereof totally submerged in the oil, thereby reducing the wear of the parts to a minimum.

A still further object of the invention is to provide, in a brake of the class described, a structure which may be largely constructed of cast metal parts requiring little machining and thus rendering it cheap of manufacture, and which may be operated by a foot pedal, ordinarily used in present practice.

Other objects and advantages of the invention will appear throughout the progress of this specification, the invention consisting in the construction, combination, and arrangement of parts hereinafter described and claimed.

In the drawings:

Figure 1, is a top view of a liquid brake embodying my invention.

Figure 2, is a vertical sectional view on line 2—2 of Figure 3.

Figure 3, is a vertical sectional view on line 3—3 of Figure 2.

Figure 4, is a fragmentary side elevation

of Figure 2, showing the control mechanism for controlling the operation of the brake.

Figure 5, is a sectional view on line 5—5 of Figure 2.

Figure 6, is a perspective view of the oscillating element forming the driven part of the brake.

Figure 7, is a fragmentary perspective view of a portion of the housing which forms part of the back pressure chambers 60 containing part of the oscillating element.

Figure 8, is a perspective view of the driving arm on the drive shaft for actuating the oscillating element.

Figure 9, is a fragmentary plan view—65 drawn to a reduced scale—of an automobile chassis frame, showing the motor and its drive shaft and my improved brake attached thereto.

Figure 10, is a diagrammatic view of the 70 oscillator element and part of the housing wherein it oscillates, to more clearly define its movements; and

Figure 11, is a diagrammatic perspective view of the oscillatory element resting on 75 the apex of a cone, to further illustrate the manner in which the body of oil resists oscillating movement of the flange of the element.

The invention comprises a casing 1, which 80 may be termed a stationary element, in that it is mounted on the frame 2 (Figure 9) as by means of the supporting strap members 3, the inner ends of the latter being here shown secured respectively to the lugs 4, 85 there being one lug projecting radially from either side of the casing. The casing is further supported on the drive shaft 4', it being provided with central, longitudinally disposed end bearings 5 and 6, the former 90 being relatively short and the latter being tubular and extending inwardly for the major portion of the length of the casing toward the short bearing. Intermediate its ends the long bearing is formed exteriorly 95 with a sphere or ball 7, the center 7' of the sphere being coincident with the longitudinal axis of the bearing.

The casing is further formed with a spherical end wall 8, concentric with said ball, 100

and spaced therefrom to form a space 9 of uniform radial width, the spherical portion of said wall extending short of a vertical plane disposed at right angles to the axis of the shaft, and being coincident with the center 7', the end wall then flaring upwardly and outwardly symmetrically about the center 7', the inner face 10 of said flaring portion radiating to the center 7', thus forming a conic wall.

The casing is further formed with a conic wall 11, similar to the conic wall 10, and disposed symmetrically relative to the latter about the center 7' whereby I secure in effect, two oppositely disposed similar cones having their apexes in the center 7'. The inner edge 12 of the wall 11 is of spherical configuration and alines with the inner face of the wall 8.

20 Fitting slidably in the space 9 is the spherical shell 13, preferably integral with the outwardly flaring cylindrical hollow extension 14, conical in shape, said extension being formed interiorly with an annular runway 14', disposed at a suitable angle to bring it into parallelism with the axis of rotation of the shaft when the extension is axially inclined to a predetermined degree relative to said axis.

30 Secured on the shaft and extending outwardly therefrom, is the lever or drive arm 15, the outer extremity of which is preferably fitted with a rotatable ball 16, which latter is disposed centrally of the runway 14' and engages therewith to roll thereon. Thus, when the shaft is rotated, oscillatory movement about the center 7' is imparted to the extension 14, the spherical shell 13 forming a more or less leak proof joint 40 with the inner edge 12 of the conic wall 11, and with a part of the inner spherical face of the wall 8.

Preferably integral with the shell 13 is the flange 17, said flange being circular in 45 outline and standing at right angles to the axis 17' of the extension 14, opposite sides of said flange being formed to radiate to the center 7', so that when the lever arm 15 is in engagement with the runway 14', the side 50 of the flange 17 will come close to or rollingly contact with the conic wall 10 or 11 (as the case may be), at a point on its circumference. The circumferential outer edge of the flange 17 is also of spherical 55 formation with 7' as its center, and is of a diameter to permit to freely move over the spherical inner wall 18 of the chamber 19, which latter is formed by the walls 10 and 11 and the shell 13. The flange 17, the 60 shell 13, and the extension 14 may be termed an oscillatory element, in that a rotary movement of the arm 15 will cause the flange to oscillate in the chamber.

The casing is further formed opposite 65 the end wall 8 with a preferably flat end

wall 20, which is joined to the conic surrounding wall 20', which latter in turn is joined to the spherical surrounding wall portion 20'', these walls being so formed as to afford ample clearance in the interior of the casing to permit free movement of the oscillatory element.

In order to render the casing liquid tight, I have provided, in connection with the wall 20, a suitable stuffing box, comprising 75 a cylindrical packing chamber 21 surrounding the shaft to receive suitable rod packing, a gland 22 slidably entering the chamber 21 to compress the packing, and a cap 22' suitably screw threaded on the exterior of the wall surrounding the chamber 21 whereby to force the gland inwardly. At the opposite end of the housing, I have also provided a stuffing box similar to the stuffing box just described, the parts having 80 similar identifying members.

At the top, the casing is formed with a preferably integral oil reservoir A, here shown rectangular in shape, and having a removable cover 23. Cutting through the floor 23' of the reservoir and leading into the chambers 19 and 19' respectively (Figure 2), are the ports 24 and 25, these ports being separated by the partition wall 26, which wall extends longitudinally of the casing, and is level at the top with the floor 23', and at its lower extremity fits slidably over the shell 13.

In vertical alinement with the wall 26 is the wall 27, which latter divides the lower portion of the chamber 19, thus forming the aforesaid chambers 19 and a companion chamber 19'. Mounted to slide over said ports is the slide valve 28, said valve being guided on opposite sides by the guide bars 28', to render it slidable at right angles to the shaft, the valve being formed with a central port 29 and cover plates 29' and 29'' on either side thereof, the port 29 being normally closed by the wall 26. As shown 100 in Figure 2, the valve holds the ports 24 and 25 normally closed, but simultaneously opens both when slid to the right, the plate 29' then resting on the wall 26, while the port 29 will register with the port 24.

Pivotedly connected to the valve, as by means of the pivot 30, is the valve rod 31, which extends horizontally through and beyond the wall of the reservoir A and has 105 slidable, pivotal connection 32 with the vertically disposed bell crank 33, said bell crank having pivotal mounting by means of the pivot 34 on the outside of the casing so as to be swingable at right angles to the shaft. A suitable valve rod stuffing box is 110 provided for the valve rod, and comprises a packing chamber 34', a gland 34'' entering said packing chamber to compress the packing therein, and a cap 35 screw threaded 115 on the exterior of the wall surrounding said 120 125 130

packing chamber to force the gland against the packing.

The rod is further formed with an annular shoulder 36 to limit the outward movement thereof, said shoulder abutting against the wall of the reservoir when the valve is in open position. An extensible spring 36' surrounding the rod, urges the valve to closed position, a pin 36'' serving as a stop to limit its inward movement. The short arm of the bell crank 33 extends outwardly and is fitted with an anti-friction roller 37.

Extending from the side of the housing is the lug 37', formed to slidably support, in vertical position, the push rod or control member 38, said member extending slidably near its top through the bracket 39, which latter is preferably suitably secured to the side of the oil reservoir as by means of the cap screws 39' (Figure 4). Thus, the control member is vertically reciprocatory and is formed intermediate its ends with an offset 40, whereby the upper portion thereof is rendered wider than the lower portion. The member is pivotally connected at its upper extremity by means of the pivot 41, to a tread lever 42, which latter is fulcrumed as by means of the pivot 43 at any suitable position on the car body (not shown) near the operator.

An extensible spring 44 rests on the lug 37' and surrounds the member and abuts at the top against the collar 45 adjustably carried by the member, whereby the push rod is urged upwardly, a stop pin 46 being provided to limit its upward movement. Normally, the offset 40, which is suitably rounded to constitute a camming surface, is normally preferably situated immediately adjacent and above the roller 37, so that the initial downward movement of the control member will cause the offset 40 to engage with the roller 37 and bodily rotate the bell crank 33 about its pivot 34, as indicated in dotted lines, thereby imparting a sliding movement to the slide valve and opening the ports 24 and 25. A further downward movement of the member will cause the roller to roll over the offset 40 and onto the inner edge 47 of the member, thus holding the valve open irrespective of any further downward movement of said member.

Referring now to the casing 1 (Figure 3), the lower portion of the casing is formed with a valve chamber 48, formed by the side walls 48' extending parallel to the division wall 27, and the end walls 48'', joining with said side walls and extending transversely of the casing and preferably parallel with the walls 10 and 11, and a bottom wall 49, jointed to said side and end walls.

The casing is further formed with a return passage way 50, which leads from the chamber 48 to the reservoir A, as is best shown in Figure 2, the passage way being

interrupted by a throttle valve 51. The throttle valve comprises a tapered plug 51', having a port 52 in register with the passage way 50, said plug being rotatably fitted in the casing and having an outwardly extending lever arm 53, which has slidable pivotal connection by means of the slot 53' and the pivot pin 54 with the control member 38. As shown in Figure 2, the valve is full open when the push rod is in its uppermost normal position. The control member is formed with a vertically disposed slot 55, adapted to slidably receive the pivot pin 54. The function of this slot is to delay actuation of the valve 51 for a period of time sufficient to permit the offset 40 to initially actuate the bell crank 33.

In open communication with the valve chamber 48 and the chamber 19, are the ports 55' and 55'', said ports cutting through the walls 10 and 11, respectively. In open communication with the chamber 48 and the chamber 19' are the ports 56 and 56', also cutting through the walls 10 and 11, respectively. Each of the four ports is provided with a similar shutter or gate valve 57, each of these valves being pivoted as by means of a horizontal pivot pin 58 supported in a pair of lugs 59 to preferably fall shut by gravity. Each valve is formed with a surrounding lip 59', overlapping the edge of the port, so that pressure applied upon the outside of the valve will effectually close the port against leakage.

Referring to Figures 2 and 6 of the drawings, the flange 17 of the oscillating element is cut away at opposite sides to form radial, outwardly opening slots 60, these slots being of a width to freely receive, respectively, the walls 26 and 27, and still permit the flange to freely be oscillated.

In operation, the casing is filled preferably with lubricating oil of a consistency to run freely, so that the reservoir A will be approximately filled, as indicated in Figure 3. The cover 23 is then placed in position. The oil is prevented from leaking by the stuffing boxes, as described, the valve plug 51' having a ground fit and being provided with adjustment nuts 61 to hold it to its seat. In filling the casing it is to be understood that the slide valve 28 is preliminarily opened to permit the oil to enter all parts of the casing, including the chambers 19 and 19'. Let it be assumed that the shaft 4' is rotating at a rate of speed customary in automobiles, which varies from four revolutions of the shaft to one of the wheels and upward. As the shaft revolves, the driving arm 15 will actuate the oscillating element, which includes the flange 17, which, as explained in the foregoing, will simulate a rolling movement simultaneously on both conic walls 10 and 11. This may be more clearly described by referring to diagrams

10 and 11 of the drawings. In diagram 10 the axis 17' (indicated in dotted lines in Figure 3) is carried around the axis of the shaft 4' by the arm 15. Obviously, the underside *a* of the flange will roll upon the conic surface 10, inasmuch as the disk is prevented from rotating by the walls 26 and 27 extending through the slots 60 (Figure 6). The same mode of operation will concurrently apply to the side *b* of the flange which will roll upon the conic surface 11'. Obviously, the oil occupying the space within which the flange oscillates (chambers 19 and 19') will be driven in a semi-circular path in a direction depending upon the direction of rotation of the shaft 4'. Thus, referring to Figure 11, when the shaft 4' is rotating in the direction indicated by the arrow *c*, the body of oil between the oscillating flange and the conic surface will be driven in the direction indicated by the arrow *c'*. A reverse movement of the shaft will reverse the flow of the oil and force it through the port 55'.

25 In Figure 11 I have shown a complete cone to illustrate the flow of the oil, and have indicated by the dotted lines the orbit of the axis of the oscillating element. In actual construction, however, the apexes of the two 30 oppositely disposed cones are cut off and replaced by the ball joint, which is resorted to for mechanically imparting oscillatory motion to a flange (which may be termed an oscillatory piston) confined in an annular 35 chamber divided into two parts, for the purpose of forcing a confined body of oil over the face of a cone in advance of the flange. The device is operated by the control mechanism as follows: Upon depression 40 of the lever 42 (Figure 4) the bell crank 33 is initially actuated to open the slide valve, as hereinbefore explained, after which the upper end of the slot 55 will have come to rest upon the pivot pin 54, so that a continued downward movement of the lever 42 45 will actuate the throttle valve by turning the plug 51' and thus change the position of the port 52 with respect to the passage way 50, thereby reducing the area of the passage 50 way 50 to vary the resistance of oil forced upward through the passage way on its return to the reservoir A.

55 Immediately after the initial actuation of the bell crank and the consequent opening of the slide valve 28, oil from the reservoir will descend through the ports 24 and 25 into the chambers 19 and 19' if for any reason these chambers are not already filled. If now the flange 17 be repeatedly oscillated from below upwards, as indicated by the arrow 60 (Figure 3), the oil will be forced through the port 56 (the valve 57 swinging outwardly) into the chamber 48, and in turn into the passage way 50 and through the 65 throttle valve back to the reservoir. Obvi-

ously, the forcing of this oil through the throttle valve will create a back pressure against the flange and thereby resist its oscillatory movement, thus imparting braking action to the shaft, which action will increase in extent as the area of the passage way is decreased by the throttle valve.

70 It will be noted that concurrently with the driving of the oil through the port 56, as just described, the oil on the opposite side of the oscillating disk will be driven upward in advance of the disk and be thereby forced through the port 24 into the reservoir, thus offering no resistance excepting that required to lift the small body of oil back into the reservoir. Thus braking action is applied to the shaft when running in one direction, the action being rendered continuous by repeated oscillations of the member, affording a continuous braking by the falling of the oil by gravity from the reservoir into the chambers 19 and 19' as fast as it is forced through the chamber 48 and the throttle valve into the reservoir. It will be noted that as the oil is forced through the gate valve 56 and into the passage way 50, a pressure is set up in said chamber, which pressure is exerted on the backs of the other three valves, forming closures for the ports 55, 55', and 56', thus holding these valves 95 closed against the slight opposing pressure existing on the opposite sides thereof, which pressure is developed by the oil which is being forced into the reservoir.

100 When the shaft is driven in the opposite direction, or reverse to that just described, with the oscillatory member positioned as shown in Figure 3, the oil will be forced from above downward past the valve shown in full lines, through the port 56', and thence into the passage way 50 as before, the oil being correspondingly forced into the reservoir on the opposite side of the member. When the oscillating member is positioned as indicated in diagram 10, and the 110 shaft is rotating from below upwards, as indicated by the arrow in Figure 3, the oil will be forced in advance of the member through the port 55'. Should the shaft be running in reverse direction, however, with the disk 115 in the position shown in diagram 10, the oil will be forced through the port 55".

120 It will be noted that the valves are totally submerged in oil, as is also the oscillating element, so that the wear of the parts is reduced to a minimum, the oil forming a cushion and rendering the device, during operation, noiseless and gradual in the application of resistance to the shaft, thus avoiding damaging shocks. When the lever 42 is released, the spring 36' returns the slide valve to closed position and opens the throttle valve to its normal, wide-open position.

125 When the brake is inactive, oil which happens to be confined on one side of the oscil-

lating member will be forced up, either through the port 24 or 25 as the case may be, to the opposite side of the member, thus avoiding any material resistance to the rotation of the drive shaft.

While the chamber in which the oscillatory member 14 oscillates will receive the oil which may leak through the joint between the edge 12 of the wall 11 and the shell 13, I have provided a small oil inlet passage 58' communicating with the oil reservoir, which inlet may be used when desired by removing the closure screw 59' (Figure 3).

15 I claim:

1. The combination with a frame and a drivable shaft supported thereon; of a hollow casing surrounding said shaft and supported on said frame to be held stationary thereby, said casing including a chamber adapted to contain liquid on one side of said shaft, a similar chamber on the opposite side of said shaft, each of said chambers having an inlet port at its top, an oscillatory member extending into the interior of both of said chambers, the inner walls of each of said chambers and said member being constructed to cooperate to force a part of the oil to occupy the lower portion of said chambers respectively when said member is oscillated, said member having operative connection with said shaft to be oscillated thereby responsive to a driving movement thereof in either direction, a discharge port for each of said chambers for discharging the oil into the lower portion of said chambers, a duct in open communication with said discharge ports and inlet ports to conduct the oil from the former to the latter, and means for varying at will the cross sectional area of said duct.

2. The combination with a frame and a drivable shaft supported thereon, of a hollow casing surrounding said shaft and supported on said frame to be held stationary thereby, said casing including a chamber extending around half of said shaft, a similar chamber, contiguous to said chamber and in lateral alinement therewith, surrounding the other half of said shaft, the inner opposite walls of both of said chambers inclining symmetrically to a common center coincident with the axis of said shaft, a port in the inclined wall of each of said chambers located below said shaft, a closure valve for each of said ports constructed and mounted to swing loosely on the outside of the inclined wall of its respective chamber, said ports communicating with the hollow of said casing, an oil reservoir at the top of said casing in open communication with both of said chambers to permit oil to flow into said chambers, a duct in open communication with the interior of said casing at a point located below said valves and leading

into said oil reservoir, manual means for arbitrarily varying the area of said duct, and an oscillatory member having operative connection with said shaft to be oscillated thereby when the shaft is actuated, said oscillatory member being constructed to effect or simulate a rolling movement with its opposite sides respectively over said inclined walls, for the purpose set forth.

3. The combination with a frame, and a drivable shaft supported thereon, of a hollow casing surrounding said shaft and supported on said frame to be held stationary thereby, said casing including a chamber extending around one side of said shaft, a similar chamber, contiguous to said chamber and in lateral alinement therewith, surrounding the opposite side of said shaft, the inner opposite walls of both of said chambers inclining symmetrically toward each other to a common center located coincident with the axis of said shaft, a port in the inclined wall of each of said chambers located below said shaft, a closure valve for each of said ports constructed and mounted to swing loosely on the outside of the inclined wall of its respective chamber, said ports being in open communication with the hollow of said casing, an oil reservoir at the top of said casing in open communication with both of said chambers to permit oil to flow into them, an oscillatory member having operative connection with said shaft to be oscillated thereby when said shaft is actuated, said oscillatory member being constructed to effect or simulate a rolling movement with its opposite sides respectively over said inclined walls, a duct in open communication with the interior of said casing at a point below said valves and leading into said oil reservoir, and manual means for arbitrarily varying the area of said duct.

4. The combination with a frame and a drivable shaft supported thereon, of a hollow casing surrounding said shaft and supported on said frame to be held stationary thereby, said casing including a chamber extending half way around said shaft, a similar chamber, contiguous to said chamber and in lateral alinement therewith, extending around the other half of said shaft, the inner opposite walls of both of said chambers inclining symmetrically to a common center which is coincident with the axis of rotation of said shaft, a port in the inclined wall of each of said chambers located below said shaft, a valve for each of said ports constructed and mounted to swing loosely on the outside of the inclined wall of its respective chamber, said ports communicating with the hollow of said casing, a duct in open communication with the interior of said casing at a point located below said valves and being in open communication with the interior of both of said chambers

at a point located at the extreme top thereof, and a manually operable throttle valve for throttling said duct.

5. The combination with a frame and a drivable shaft supported thereon, of a hollow casing surrounding said shaft and supported on said frame to be held stationary thereby, said casing including a chamber extending from a point located above the shaft around one side thereof to a point located below the shaft, a similar chamber, contiguous to said chamber, extending around the opposite side of said shaft, said chambers lying in a common plane at right angles to said shaft, an oil reservoir located above said chambers and being in open communication with both, to permit oil to fall into the chambers, a duct in open communication with the interior of said casing 10 at a point located below said chambers and leading into said oil reservoir, manual means for throttling said duct at will, an oscillating member operatively connected to the shaft to be oscillated thereby responsive to a driving movement thereof, a part of said oscillating member extending into both of said chambers, the walls of both of said chambers and said oscillating part being constructed to cooperate responsive to an oscillating movement of said oscillating member to tend to force part of the oil in one of said chambers to the bottom thereof when the shaft is rotating in one direction, and to force a part of the oil to the bottom of the other of said chambers when the shaft is running in the opposite direction, and valve mechanism for each of said chambers adjacent the bottom thereof, said mechanism including a port in open communication with said duct to permit the oil forced to the bottom of said respective chambers to be discharged.

In testimony whereof I affix my signature.
PETER MEYER.
